(57) **CLAIM**

The ornamental design for a ventilator hood, as shown and described.

DESCRIPTION

FIG. 1 is a top front isometric view of a ventilator hood according to the present invention.

FIG. 2 is a bottom front isometric view of the ventilator hood of FIG. 1.

FIG. 3 is a front view of the ventilator hood of FIG. 1.

FIG. 4 is a rear view of the ventilator hood of FIG. 1.

FIG. 5 is a left side view of the ventilator hood of FIG. 1.

FIG. 6 is a right side view of the ventilator hood of FIG. 1.

FIG. 7 is a top view of the ventilator hood of FIG. 1; and,

FIG. 8 is a bottom view of the ventilator hood of FIG. 1.

The broken dashed lines depict a part of the ventilator hood that forms no part of the claimed design.

1 Claim, 7 Drawing Sheets
